UNITED STATES PATENT OFFICE.

PETER JOSEPH MANN, OF PITTSBURGH, PENNSYLVANIA.

STREET OR STATION INDICATOR.

1,009,253.

Specification of Letters Patent. Patented Nov. 21, 1911.

Application filed October 19, 1909. Serial No. 523,419.

To all whom it may concern:

Be it known that I, PETER J. MANN, citizen of the United States, residing at Pittsburgh, in the county of Allegheny and State of Pennsylvania, have invented certain new and useful Improvements in Street or Station Indicators, of which the following is a specification.

This invention comprehends certain new and useful improvements in that class of station indicators that are designed to be used in traction or steam cars for the purpose of automatically displaying the names of the different streets or stops, the invention being designed to also display an advertisement at the same time it displays the name of the next station or street, so that the passengers will have their attention directed to the advertising matter.

The primary object of the present invention is an improved apparatus of this character which will be entirely automatic in its action, positive, sure and otherwise efficient in operation and which will be composed of comparatively few and simple parts that may be easily manufactured, assembled, and adjusted when necessary, and which will not be liable to get out of order.

With this and other objects in view, my invention consists essentially in a street or station indicator embodying a display web adapted to wind from and on revoluble spools said spools being intermittently actuated at the desired time and automatically and positively stopped after each actuation, by electrical devices the circuits of which are automatically controlled. And the invention also consists in certain constructions, arrangements and combinations of the parts that I shall hereinafter fully describe, and then point out the novel features in the appended claims.

For a full understanding of the invention, reference is to be had to the following description and accompanying drawings in which:

Figure 1 is a side elevation of my improved apparatus, one section, or half of the casing being removed to show the interior parts, and a small portion of the mechanism being shown in section; Fig. 2 is an end elevation of the mechanism with the end plate removed, this view looking from the left of Fig. 1. Fig. 3 is a top plan view with the top plate of the casing omitted; Fig. 4 is a detail perspective view of the

web controlled switch which forms part of the circuit opening and closing mechanism: Fig. 5 is an enlarged detail sectional view of that roll shaft which is directly connected to the actuating mechanism or motor: Fig. 6 is a detail sectional view of one of the retarding devices that are designed to prevent the rolls from over-running after the power has been shut off, the section being taken on the line 6—6 of Fig. 5, looking in the direction of the darts; Fig. 7 is a detail view partly in section on line 7—7 of Fig. 3, illustrating more clearly the travel of the web from one roll to the other; Fig. 8 is an enlarged detail view of a portion of the actuating mechanism with parts in section. Figs. 9 and 10 are detail views of the motor switch which is employed; and Fig. 11 is a diagrammatic view of the wiring.

Corresponding and like parts are referred to in the following description and indicated in all the views of the accompanying drawings by the same reference characters.

The display web 1 which is adapted to contain the names of the streets, stations or stops in succession, together with other display matter such as advertising is mounted to wind from and on spools 2 and 3 mounted in a casing A which may be of any desired construction and design, suitable for inclosing and holding the operating parts. As best illustrated in Fig. 7, the web 1, as it passes from one roll or spool to the other travels over guide rollers 4 toward and around a similar guide roller 5, the casing being so formed, preferably, as illustrated in Fig. 2, that it will display the different stops or stations and the advertising matter or the like at both sides of the attenuated lower portion of the casing simultaneously, as in my Letters Patent of the United States, #888,126, dated December 11, 1906.

6, 6^a, designate the two shafts of the spools 3 and 2 respectively. Each of these shafts is journaled in brackets or similar bearings secured in any desired way within the casing A, and each shaft is provided at one end with a ratchet wheel 7 designed to be engaged by a driving pawl 8 pivotally connected to a pawl carrying disk 9, and pressed into engagement with its corresponding ratchet by means of a spring as best seen in Fig. 5. In order that both spools may be driven when one of them is actuated, the two spools are connected to

gether by means of a belt 10 which is held under suitable tension by means of a tension roller 11 journaled in one arm of a bell crank lever 12. This lever is held under tension by means of a spring 13 connected thereto and to a suitable stud screwed in the top or cover plate of the casing as best illustrated in Figs. 2, 7 and 8.

The spool connecting belt 10 extends over 10 grooved belt wheels or pulleys 14 which are in the form of rings mounted between the pawl plates and complementary friction disks 15, packing or friction rings 16 being interposed between these parts as best seen in 15 Fig. 5. One of the friction disks 15 and pawl carrying disks 9 extend on through their bearings in the casing and form a connection for a worm wheel 17 preferably secured thereto by dowel pins 17^a. 18 designates adjusting nuts screwed on the outer end of the hub of the belt carrying disk 9 which is thus extended, as best seen also in Fig. 5. The worm wheel 17 meshes with the worm 19 on the worm shaft 20 of the motor 21 (see 25 Fig. 8). 22, 22^a designate clutch spools splined or feathered on the shaft 20, the spools being adapted to slide longitudinally on said shaft and being designed for engagement alternately with the stationary 30 clutch member 23, and the relatively movable clutch member 24 respectively. The clutch member 24 is secured on a threaded portion of the motor shaft 20 and is prevented from backward movement on said 35 shaft by means of a split or spring clamp collar 25 as best seen in Figs. 2 and 8. The clutch spools 22 and 22^a are slightly spaced from each other as shown and between these is received the forked arm 26 of a bell crank 40 shipper lever, the forks of said arm carrying rollers. The other arm of this shipper lever is pivotally connected to the plunger 28 of an electromagnet 29. The first named arm 26 is extended upwardly above the 45 clutch spools 22, 22^a as indicated at 30, and is pulled in one direction by means of a contractile spring 31 and is operatively connected to the motor switch 32 to open and close the electric circuit.

50 At predetermined distances in the display web 1 a series of openings 33 is formed, said openings being adapted to register successively with a roller 34 of the web actuated switch 35 so as to complete the circuit 55 through the lower guide roller 5 and the spring switch contact 36 at one end of said roller (see Fig. 1).

37 designates two retarding disks, that are mounted on the shafts 6, 6^a as best seen in 60 Figs. 3 and 6, said disks being designed to prevent the spools from over running when the power is withdrawn; each of these retarding disks 37 carries a pawl 38 designed for engagement with a ratchet 10 secured on 65 the respective shafts, said pawl being

pressed into engagement with the ratchet by means of a spring 39.

41 designates a retarding belt which extends over the groove in the periphery of the disk 37. This retarding belt is secured at one end as by a wedge 42^a as indicated in Fig. 6, to a stationary lug 42 of the casing, and passes over a guide roller 43 mounted in a bearing 44. The other end of the retarding belt is held under tension by means of an adjusting nut 45.

In describing the practical operation of my improved street or station indicator, it will be assumed that all of the working parts are stationary and ready to begin working. The magnet 29 is energized, the magnetic circuit being normally closed. As the car approaches a street crossing or station, the magnetic circuit is opened by an external device, either upon the track or trolley, and this deenergizes the magnet 29, thereby allowing the shipper lever spring 31 to pull the clutch spool 22^a into engagement with the motor shaft clutch member 24. At the same time, the clutch lever also closes the motor switch 32 (Fig. 8) thereby closing the motor circuit and causing the motor to rotate. This rotation manifestly effects the driving of the shaft 20 and worm 19 which is fastened rigidly thereon and the worm 9 drives the worm wheel 17 which is fastened to the friction disk 15 which in turn drives its belt wheel 14 and pawl carrying disk 9. As the pawl 8 of said disk engages its ratchet wheel 7, it will drive the latter, and will also in turn drive the spool 3 through the instrumentality of the shaft 6. Both spools are thus driven by the belt 10 and continue to rotate until one of the slots or openings 33 in the display web 1 is brought into registry with the display web 35, at which time the magnetic circuit is completed through the lower guide roller 5 and lower roller contact member 36, the track or trolley switch already referred to having become closed shortly after the motor started to rotate. The tape switch 35 and lower roll contact switch 36 are embodied in the magnetic circuit which also includes the electromagnet 29 by suitable wiring. The magnetic circuit being thereby completed when the circuit is closed between the points 34, 35 and 36, the magnet 29 becomes energized, thereby throwing the spools 22, 22^a from the motor clutch 24 into engagement with the stationary clutch member 23, effecting a positive braking action on the shaft 20 and causing the same and the other parts to come at once to a standstill, while at the same time the bell crank lever 26, 27 is rocked in a direction to move its switch arm 30 to the left in Fig. 8, thereby opening the motor switch 32. This brings the mechanism to a full stop and completes the cycle of operation.

If the display web is to be wound from the left hand spool to the right hand spool, the operations are the same except that the belt wheel on the right hand side is driven by the belt wheel on the other spool, through the driving belt 10. If the web is wound from the left hand spool upon the right hand spool, the pawl of the ratchet wheel on the left hand side will click over the wheel until the amount of display web on the right hand spool exceeds that on the left hand spool, whereupon the pawl and the ratchet become locked, and the difference in speed between the two spools is taken care of by the friction parts, the proper tension being obtained by means of the adjusting nuts 18.

In the preferred construction of the device the worm shaft 20 and motor shaft 20^a are two separate or distinct parts. The clutch 20 consisting of the spools 22 and 22^a drives the worm shaft 20 by means of a feather or key working in a groove in the shaft, and said clutch is driven by means of the motor clutch 24. The motor has no way of driving the worm shaft except by means of this clutch. The object of this is to allow the motor to die down gradually after the current has been shut off, while the clutch 22 and 22^a and all mechanism driven by it is brought to a sudden stop by means of the stationary clutch member 23.

For the details of construction of the motor switch reference is to be had to Figs. 9 and 10. In these views *a* designates a maple switch block; *b* a fiber hanger for the switch bar *c*; *c* the switch finger clamp; and *d* the fiber insulation for the switch bar. *f* designates the switch-operating arm; *g* the phosphor bronze contact fingers; *h* contact screws, and *i* the connectors to the wire. *k* represents the shaft or axis upon which the switch bar turns, and *l* the phosphor bronze connecting arm of the contact fingers.

For a better understanding of the circuits by which the different parts are operated, reference is to be particularly had to Fig. 11. The trolley contact *G* coming in contact with the trolley trip *H* causes the current to flow through the trip magnet *E* which raises the contacts *F*; thereby opening the circuit in the magnet *29*. The plunger or movable core of the magnet *29* thereupon moves downward, actuated by gravity and assisted by the spring *31* acting on the arms *30* and *36*. The downward movement of the plunger closes the motor switch *32*, and the motor circuit being closed, the motor shaft *21^a* will revolve, and through the gears before described will wind the web or tape from one spool over the contact roller *5* and the contact wheel *34*. Thereupon the circuit in the magnet will be closed, causing the core thereof to be moved up, and opening the motor circuit and thereby stopping the motor and bringing the machine to a stand-

still. The motor then remains stationary until the trolley contact *G* comes in contact with the next trolley trip *H*, when the above described operation is repeated. When the last opening *33* in the tape operates, the end being unwound is positioned between the contacts *34* and *35*, the reverse switch *B* is thrown to the opposite position, thereby reversing the direction of rotation of the motor shaft *21^a* and causing the tape to be wound in the reverse direction. *A* designates the junction or terminal blocks, *C* the snap switch which cuts the apparatus out of circuit whenever desired, and *D* represents a double pole fuse block with plug fuses.

It is to be understood that my invention is not limited to the exact constructions, arrangement and proportion of the parts specified in the foregoing description and illustrated in the accompanying drawings, but that various changes may be made without departing from the scope of the invention as defined in the appended claims.

Having thus described the invention, what is claimed as new is:—

1. An indicator of the character described, embodying a display web, spools from and on which said web is adapted to wind, a motor for driving said spools, an operative connection between said motor and one of the spools, said connection including two separate shafts, one of which is a motor shaft, and a clutch spool interposed between and mounted on said shafts, a shipper lever operatively connected to said clutch spool, means tending to hold the shipper lever in a position where the clutch spool will establish the operative connection between the motor shaft and the other shaft, an electromagnet provided with a plunger connected to the shipper lever and arranged upon the energization of the magnet to move the shipper lever in a direction to disconnect the motor shaft from the other shaft, means for automatically and intermittently energizing said magnet, and a brake with which the clutch spool is adapted to engage upon the energization of the magnet.

2. An indicator of the character described, embodying a display web, spools from and on which said web is adapted to wind, a motor for driving said spools, a clutch arranged to make and break an operative connection between the motor and one of the spools, a shipper lever operatively connected to the clutch a switch arm carried by said shipper lever and arranged to open and close a circuit for the motor, an electromagnet provided with a plunger operatively connected to said shipper lever, means tending to hold the shipper lever in a position where the clutch will make the operative connection between the motor and the spool and the contact arm will close the motor circuit,

and means for automatically, intermittently energizing the electromagnet whereby to throw the shipper lever in a direction to effect the breaking of the operative connection between the motor and the spool and the opening of the motor circuit.

3. An indicator of the character described, embodying a display web, spools from and on which such web is adapted to wind, an electric motor for driving said spools, an operative connection between said motor and one of said spools, such connection including two separate shafts one of which is a motor shaft, and a clutch interposed between and mounted on said shafts a shipper lever operatively connected to said clutch, a contact arm carried by said shipper lever and arranged to make and break the circuit for the motor, means tending to hold the shipper lever in a position where the contact arm will close the motor circuit and the clutch will make or establish the operative connection between the motor shaft and the other shaft, an electromagnet provided with a plunger connected to the shipper lever and arranged upon the energization of the magnet to move the shipper lever in a direction to break the motor circuit and disconnect the motor shaft from the other shaft, means for automatically and intermittently energizing said magnet, and a brake with which the clutch is adapted to engage upon the energization of the magnet, whereby the spools will be stopped, while the motor will be permitted to move free and die down.

4. An indicator of the character described, embodying a display web, spools from and on which said web is adapted to wind, ratchets carried by the shafts of the respective spools, pawls engaging said ratchets, pawl carrying disks to which the pawls are connected, a driving connection between said disks, one of said disks being provided with an extended hub, a worm gear on said hub, a worm meshing with said gear, a shaft carrying the worm, a motor provided with a shaft disposed in longitudinal alinement with the worm shaft, a clutch member mounted on the motor shaft, a stationary clutch member set opposite the other clutch member, a clutch spool interposed between the two clutch members and mounted on said shafts, a shipper lever connected to said clutch spool, an electromagnet provided with a plunger connected to the shipper lever, and means for intermittently energizing and deenergizing said magnet.

5. An indicator of the class described, embodying a display web, spools on and from which said web is adapted to wind, an electro-motor provided with a driving shaft, a clutch member mounted on said shaft, another shaft in longitudinal alinement with the motor shaft, but distinct therefrom, a driving connection between one

of said spools and said last named shaft, a stationary clutch member, clutch spools mounted between said clutch members and arranged to alternately engage the same upon the movement of the clutch spools in one direction or the reverse longitudinally of said shafts, a shipper lever operatively connected to said spools, a contact arm carried by the shipper lever arranged to make and break the motor circuit, means adapted to hold the shipper lever in a position where the contact arm thereof will maintain the motor circuit closed and a clutch spool will engage the clutch member of the motor shaft, an electromagnet provided with a plunger connected to said shipper lever, and means for automatically and intermittently producing in said electromagnet a condition in which the plunger will be moved in a direction to swing the shipper lever to a position where the other spool will engage the stationary clutch member and the contact member of the shipper lever will open the motor circuit.

6. An indicator of the character described, embodying a display web, spools from and on which said web is adapted to wind, shafts on which said spools are mounted, ratchets carried by said shafts, pawls engaging the respective ratchets, pawl-carrying disks to which said pawls are secured, friction disks arranged contiguous to the pawl disks, means for driving one of said friction disks and its corresponding pawl disk, band wheels mounted on and between the corresponding portions of the friction disks and the pawl carrying disks, and a belt passing around said wheels.

7. An indicator of the character described, comprising a casing, a display web in said casing, spools from and on which said web is adapted to wind, shafts on which the respective spools are journaled, ratchets connected to said shafts, pawls engaging said ratchets, pawl carrying disks to which said pawls are secured one of said disks being formed with an extended hub, a worm wheel mounted on the hub, means including a worm meshing with said worm wheel for driving said disk whereby to effect the rotation of one of the shafts of said spool, and a connection between said shafts of the respective spools whereby the spools will be rotated simultaneously.

8. In an indicator of the character described, a display web, spools from and on which said web is adapted to wind, shafts on which said spools are mounted, retarding disks mounted on said shafts, pawls secured to the disks, ratchets secured to said shafts and engaged by said pawls, retarding belts extending around and engaging said disks, means for tensioning said belts, and means for rotating the spools.

9. In an indicator of the character de-

scribed, a display web, spools from and on which said web is adapted to wind, shafts on which said spools are mounted, retarding disks mounted on said shafts, pawls secured to the disks, ratchets secured to said shafts and engaged by said pawls, retarding belts extending around and engaging said disks, means for tensioning said belts, means for rotating the spools, means for driving the

shaft of one of said spools, and an operating connection between such shaft and the shaft of the other spool.

In testimony whereof I affix my signature in presence of two witnesses.
